UNITED STATES PATENT OFFICE.

CURTIS L. CRUVER, OF CHICAGO, ILLINOIS.

POWDER RECEPTACLE.

Application filed December 27, 1920. Serial No. 433,324.

To all whom it may concern:

Be it known that I, CURTIS L. CRUVER, a citizen of the United States, residing at Chicago, in the county of Cook and State 5 of Illinois, have invented certain new and useful Improvements in Powder Receptacles, of which the following is a specification.

The invention relates more particularly 10 to small powder receptacles commonly known as vanity cases which are carried about the person and contain face powder. Heretofore such cases have usually been constructed with a cover closing upon the body 15 of the case with a snap engagement between the rim of the cover and the wall of the body portion. In such construction the cover becomes loose with use and is liable to become separated from the case and permit the loss 20 of its contents in the pocket or handbag of the person carrying it.

The object of this invention is to provide easily manipulated and simply constructed 25 fastening means for the cover of a vanity case which will withstand use and effectively secure the cover in position at all times.

The construction and arrangement of my 30 device more fully appears in the following description and in the accompanying drawing, of which Figure 1 is a plan view of the body of a vanity case. Fig. 2 is a plan view of the mirror-equipped inner side of the cover. Fig. 3 is a cross sectional view taken 35 through the center of the assembled case and Fig. 4 is a perspective view of the unitary spring fastener by which the cover is secured to the body.

The case is formed of a body section and 40 a cover section commonly constructed of metal covered on the outside with a decorative coating of enamel, celluloid or similar material. The body section comprises a dished back portion having an inwardly inclined flange 2 formed on its outer edge. An 45 annular side wall 3 extends within the inclined flange 2 and is constructed with its lower edge 4 expanded in permanent engagement with the inner surface of the flange 2. The upper edge of the annular side wall 3 50 is turned inwardly to form a lip 5 running about the periphery of the side wall.

A diaphragm 6 dished oppositely from 55 the back portion is positioned within the flange 2 having its outer edge secured therein by the side wall 3. A similarly dished diaphragm 7, of less diameter than the dia-

phragm 6, is secured thereto at its center by an eyelet 8 forming a pivot about which the diaphragm 7 may be rotated. The space between the back portion 1 and the diaphragm 6 is utilized as a storage chamber for the face powder. An aperture 9 formed in diaphragm 6 and a similar aperture 10 formed in the upper diaphragm 7, may be registered by rotating the upper diaphragm 65 to afford an opening for filling the supply chamber. The upper diaphragm 7 also has a series of perforations 11 which may be brought into register with the aperture 9 for the limited discharge of powder from 70 the supply chamber. The rotation of the diaphragm 7 is effected by means of a boss 12 struck up from the surface of the dia- phragm.

The cover section comprises a slightly 75 dished member 13 having an inwardly inclined flange 14 about its outer periphery which is adapted to fit slidably over the side wall 3 of the body section of the case. A mirror 15 may be secured on the inner 80 side of the cover, being held in position by a retaining ring 16, having its outer edge secured within the inclined flange 14 and its inner edge overlying the outer edge of the mirror 15. Movement of the mirror within 85 its fastening is prevented by the insertion of a cushion 17 of felt or similar material between the back of the mirror and the member 13.

At diametrically opposite points in the 90 retaining ring 16, slots 18 are cut in the portion of the ring extending between the flange 14 and the mirror 15. A unitary leaf spring member 19 extends beneath the mirror, being held in position by the cushion 95 17, and having its free ends 20 bent upwardly and extending through the slots 18 a substantial distance beyond the flange 14. The extremities of the bent ends are turned slightly inward as at 21.

It will now be apparent that upon assembling the cover with the body section, the spring ends 20 will slidably engage the inner surface of the side wall 3, passing over the inturned lip 5 and effecting a detachable but secure fastening of the cover with the body section, the lip 5 serving to restrain the removal of the cover until sufficient force is applied to withdraw the spring ends from the inturned lip.

The free ends 20 extend downwardly a sufficient distance so that their engagement

with side walls 3 is accomplished before flange 14 comes into contact with the walls, thereby causing the ends to guide the cover to exact alinement with the body section 5 preparatory to placing the cover section on the body section.

I claim as my invention:

In a device of the class described, a body section having a projecting cylindrical side wall, said wall having an inturned lip on its outer edge, a cover section having a peripheral flange adapted to receive said side wall in sliding engagement, a mirror interiorly mounted in said cover, a leaf spring 10 positioned between said mirror and cover 15

section and having its ends bent outwardly to form a pair of oppositely disposed spring fingers projecting beyond said peripheral flange, said fingers being convexed outwardly to yieldingly slide over said lip and engage the surface of said cylindrical side wall, thereby positioning the cover section in exact alinement with the body section and guiding said sections to sliding engagement and yieldingly holding said cover section in closed position on the body section. 20 25

In testimony whereof, I have hereunto set my hand.

CURTIS L. CRUVER.
